UNITED STATES PATENT OFFICE.

JOHN ERICKSON, OF CHICAGO, ILLINOIS, ASSIGNOR, BY MESNE ASSIGNMENTS, TO AUTOMATIC ELECTRIC COMPANY, A CORPORATION OF ILLINOIS.

AUTOMATIC TELEPHONE SYSTEM.

1,354,605.

Specification of Letters Patent.

Patented Oct. 5, 1920.

Application filed December 30, 1904. Serial No. 238,903.

To all whom it may concern:

Be it known that I, JOHN ERICKSON, a citizen of the United States of America, and resident of Chicago, Cook county, Illinois, have invented a certain new and useful Improvement in Automatic Telephone Systems, of which the following is a specification.

My invention relates more particularly to 10 that well-known type of automatic telephone system in which each subscriber's line is provided, at the central station or other suitable place, with a so-called "first selector-switch", and in which there are also 15 a suitable number of so-called "connector-switches", each "first selector" being individual to a subscriber's station, and employed by the subscriber, when calling a number, for automatically selecting an 20 idle trunk-line, and the said "connector-switches" being preferably less in number than the subscribers' stations—that is to say, each "connector-switch" being common to a number of subscribers' lines, and employed, after the proper trunk-line 25 connection has been established through the medium of the "selector-switch", for making the final connection with the line of the called subscriber.

30 My invention has special reference to an automatic telephone system of the foregoing general character in which the so-called "vertical" and "rotary" relays of the said "first selector-switches", or other individual switches, are normally bridged across the subscribers' lines.

Generally stated, the object of my invention is to provide means for automatically cutting off, or opening up, the bridge 40 containing said relays, or other electromagnets, of the called subscriber's line, when a connection between such line and the line of the calling subscriber is finally established, so as to prevent short circuiting of the voice-currents through the said bridge while the subscribers are talking, and, among other things, to prevent the said relays from chattering and from being operated when the ringing current is thrown 45 onto the line for the purpose of ringing the bell at the called subscriber's station.

A special object is to provide a construction and arrangement whereby each "first selector-switch", or other suitable individual switch, may be provided with a bridge

cut-off relay, and whereby the said bridge cut-off relays may, in each case, be energized by the flow of current through a circuit which is closed as soon as the "connector-switch" establishes connection with the 60 called subscriber's line.

It is also an object to provide certain details and features of construction tending to increase the general efficiency and serviceability of a bridge cut-off arrangement of this particular character.

To the foregoing and other useful ends, my invention consists in matters herein-after set forth and claimed.

Figure 1 of the accompanying drawing 70 is a diagram illustrating, in as simple a manner as possible, an automatic telephone system embodying the principles of my invention.

Figs. 2 and 3 when taken together 75 represent a complete connection from a calling to a called telephone line through a first selector, second selector, third selector and connector of the type of system which was installed in Los Angeles, California. These 80 figures show the details of the circuit arrangements completely and are the basis for the schematic diagram shown in Fig. 1.

As thus illustrated, the two subscribers' stations A and B are shown with their 85 lines fully connected up through the medium of a trunk-line and a "first selector" and a "connector" switch. The "first selector-switch" of the line leading to the subscriber's station A is represented by the so-called "vertical" and "rotary" relays D and E, and also by the bridge cut-off relay F. Other familiar elements of the said "first selector-switch" consist of the "side-switch" G and the "vertical" and "rotary" wipers H and I. The so-called "normal post arm" J will also be recognized as a part of a well-known construction of "first selector-switch."

The "connector-switch" is represented by 100 the usual "vertical" and "rotary" relays K and L which are bridged across the trunk-line conductors M and M¹; and the bridged back-release relays N, which are a part of the said "connector-switch," are also shown. 105 The "private" wiper O of the so-called "side-switch" of the "connector-switch" is also illustrated. And the "vertical," "private" and "rotary" wipers of the rotary shaft of the said "connector-switch" are indicated at 110

P, Q and R; it being understood that these are the usual wipers for engaging the contacts of the "vertical," "private" and "rotary" banks. At the right of the diagram, 5 the "first selector" of the called subscriber is represented by the "vertical" and "rotary" relays S and T, the "side-switch" U and the bridge cut-off relay V. This switch is also further identified by the "vertical" and 10 "rotary" wipers W and X of the switch-shaft, and by the "normal post arm" Y.

It will be readily understood that the apparatus at sub-station A is connected with the "first selector-switch" allotted to this 15 station, and also with the bank-contacts of one or more "connecting-switches," through the medium of line wires a and a¹. In a similar manner, it will be seen that the apparatus at sub-station B is connected with the "first selector-switch," and also with the bank-contacts of one or more "connecting-switches," through the medium of line wires 20 b and b¹.

At the central station, condensers Z are 25 interposed in the talking circuit at opposite sides thereof, and a centralized source of current Z¹ is employed for furnishing the current necessary for operating the various relays.

30 As shown, the connection has been fully established between the two subscribers' lines, and the circuit is in condition for talking. It will be readily understood that the apparatus at the sub-stations may be of any suitable known or approved character. Furthermore, the method of connecting up 35 the two subscribers' lines is well understood, and need not be described. Only such portions of the "first selector-switches" and the "connector-switch" have been shown as are necessary to a clear understanding of my invention. The parts or elements shown are sufficient to enable those skilled in the art 40 to readily recognize or identify the "selector" and "connector" switches.

Prior to my invention, and as is well known, it had been the practice to employ the "side-switch" G of the "first selector" for opening the bridge across the conductors 50 of the talking circuit through the line relays of the selector when the calling subscriber operates the said "selector". Consequently, this bridge will give no trouble whatever when the "first selector-switch" is operated, 55 as at such time it is cut off by the action of the "side-switch." In order, however, that the said bridge may also be cut off or opened up when the switch is idle—that is to say, in order that the similar bridge of the called

60 subscriber's "first selector-switch" may be cut off or opened up, it is found desirable and advantageous to provide each so-called "first selector-switch" with a bridge cut-off relay. The bridge cut-off relay F is, of course, not operated by the act of the sub-

scriber at station A in making connection with the line leading to station B. On the other hand, however, the bridge cut-off relay V is brought into action, and made to perform its function, when the subscriber at 70 station A causes the "connector-switch" to establish connection with the line of station B. In other words, as soon as the subscriber at station A has made connection with the called line, the circuit of the bridge cut-off 75 relay V is closed; and this, it will be seen, opens up the normally-closed contacts v, which are interposed in the bridge between the relays S and T. The "normal post arm" of the "first selector" at the left of the figure 80 moves upward, when the said "selector" is operated, and in so doing, causes the spring j to move out of engagement with the contact j¹ and into engagement with the contact j². It will be seen that the contact j¹ is connected with one terminal of the coil of the bridge cut-off relay F, while the contact j² is grounded at j³. The spring j is, 85 of course, connected with the "private" bank-contacts of one or more "connector-switches." In this way, the circuit of the relay F is opened as soon as the "first selector-switch" of the calling subscriber is operated, thereby making it impossible for 90 any of the various currents to operate the said relay. The "first selector-switch" of the called party, however, remains in its normal condition, and consequently the "normal post arm" Y keeps the spring y and the contact y¹ pressed tightly together, and 95 keeps the said spring out of contact with the other contact y², which is grounded at y³. Such being the case, it is evident that a circuit is closed through the coil of the bridge cut-off relay V as soon as the "private" 100 wiper O of the "side-switch" of the "connector" is operated and moved to the position shown in drawings. In other words, the "connector-switch", when operated by the calling subscriber, closes a circuit from 105 the battery Z¹ through the conductors 1 and 2, through the coil of relay V, to the conductor 3, thence through the contacts y¹ and y to the conductor 4, through the "private" bank and the "private" wiper Q of the 110 switch-shaft, through the "private" wiper O of the "side-switch" of the "connector", and thence through the ground connections 5 and 6 to the other pole of the battery. This, as stated, opens up, or practically cuts off, 115 the bridge existing across the calling subscriber's line, by reason of the unoperated condition of the "first selector-switch" allotted to the called subscriber's station.

In this way, while the construction of 120 the "first selector-switch", prior to my invention, was of such character that the bridge through the "vertical" and "rotary" relays would be opened when the switch was operated, it is now evident that I pro- 125

vide an arrangement whereby this bridge will also be opened when the "first selector switch" remains unoperated. In other words, I provide an arrangement whereby the calling subscriber may, in addition to opening the bridge of his own "selector", also opens the bridge of the called subscriber's "selector."

With an arrangement of the foregoing character, it is obvious that the calling subscriber, in throwing ringing current onto the line of the called subscriber, cannot possibly operate the "vertical" and "rotary" relays of the called subscriber's "selector", as no ringing current can pass through the coils of these relays. Also, the cutting off of the called subscriber's relay bridge in this manner tends to increase the efficiency of the talking circuit, as it reduces the number 20 of bridges or connections through which the voice currents might be short circuited or diverted from the talking circuit.

In addition to opening the normally closed contacts v , energizing the relay V also separates the third contact v^1 from the other two. This, it will be seen, not only produces a break in the bridge between the two relay-coils, but also disconnects both coils from the battery Z^1 . At the left of the diagram, the three contacts 29, 30 and 31 all remain in contact with each other; but although this leaves the battery connected with the coils of the relays E and D , it will be seen that nothing undesirable results therefrom, owing to the fact that the "side-switch" G has been operated in such manner as to disconnect both relays from the line circuit.

It will be understood that the wires, 7, 8 and 9 lead, respectively, to the "rotary", "vertical" and "private" bank-contacts of one or more "connector-switches."

By cutting off or opening up the bridge across the called subscriber's line there is then no danger of the called subscriber's individual switch, such, for example, as the first selector shown, being operated when signaling current is transmitted to the called substation. In a bridging system, and with the bridge left across the called line, the signaling of the called subscriber would be liable to energize the relays of the called subscriber's first selector or other individual switch, and thus operate the same to an off-normal position. Should the called subscriber afterward attempt to make a call he would not obtain connection with the desired line, or would experience other trouble. In other words, the transmission of the signaling current over the called line would cause the called subscriber's individual switch to seize a trunk line, which trunk line would be uselessly rendered busy during conversation between the two subscribers. All this trouble is avoided by the use

of my bridging system involving means for cutting off or opening up bridges.

Following is a description of the telephone system as installed in Los Angeles, California, and which is given here as a basis to the schematic diagram of Fig. 1, and in order to enable any one skilled in the art to produce a system such as shown in Fig. 1 having in mind the details of the various mechanisms and circuits as herein-after set forth.

The system shown in Figs. 2 and 3 consists of a calling telephone A' ; a selector E' individual thereto and having access through a second selector F' to a third selector G' , (Fig. 3). The selector G' in turn has access to a connector switch H' (Fig. 3) which in turn has access to called lines such as B' . It will be understood that in the system a part of which I am herein describing, there were as many switches E' as there were telephone lines and that there were also a plurality of switches such as F' , G' and H' accessible to calling subscribers in common.

I have shown only those switches necessary for use when a calling subscriber desires to extend a connection to a called subscriber and will explain the succession of operations which take place when the calling subscriber A' removes his receiver and operates his calling device to set up a connection to a called subscriber B' (Fig. 3).

The subscribers' substations are of a type well known to those skilled in the art and comprise the usual talking instrumentalities and a calling device which is adapted after being rotated by the subscriber to first ground the vertical line conductor 10 a predetermined number of times, and then to ground the rotary line conductor 11 once. A ringing key 12 is also supplied by means of which the vertical line conductor may be connected to ground.

Assuming the directory number of the called line shown is 22220, then the calling subscriber will first remove his receiver from the switch hook and then operate his calling device in accordance with the various digits of the called number. As the switch hook rises when the receiver is removed, the springs 13 close to connect ground to the ground post of the calling device, to the front contact of the ringing key, and to the spring 14 of the release springs.

The subscriber now inserts a finger in the finger hole #2 of the calling device and as the device returns to normal after operation ground is first connected via spring 13 to the vertical line 10 twice and thence through the vertical line relay 16 and springs of cut off relay 17 to battery. Relay 16 responds to deliver two impulses from ground through its springs, main spring and back contact of private magnet 18, and through vertical

magnet 19 to battery. Magnet 19 operates to step the wipers two steps, opposite the second level of the bank. At the same time the wipers moving vertically cause the off 5 normal springs to operate to open the circuit of relay 17 and connect ground to the private normal conductor to make the line of substation A' busy. Immediately after these two impulses are delivered to the vertical line, the tooth 20 of the impulse wheel connects ground once to the rotary line conductor 11 thence through rotary line relay 21 and through the springs of cut off relay 17 to battery. Relay 21 responds to deliver 10 one impulse from ground through its springs, and through the private magnet 18 to battery. The private magnet operates in response to this impulse to step the side switch wipers to their second position.

15 20 In second position a circuit is completed from ground through second position of side switch and through the rotary magnet 22 and its interrupter springs to battery. The rotary magnet operates once to step the line and private wipers onto the first set 25 of contacts in the level opposite which they stand. The rotary magnet also has an extension on its armature which acts to pull up the armature of the private magnet 18, so that, if the first trunk line in this level 30 is idle and no ground therefore present on the private contact thereof, then the side switch will immediately step to third position as the rotary magnet falls back to prevent further operation of the rotary magnet 35 and to extend the connection through from the line to the line wipers.

However, assume that the first trunk line 40 is busy and ground present on its private contact, then a circuit will be closed from ground through the private contact and wiper 23, through back release relay 24, side switch wiper 25 in second position, and through private magnet 18 to battery. The 45 resistance of private magnet 18 prevents the energization of relay 24 at this time but the private magnet 18 is energized and holds its armature in its attracted position to prevent the release of the side switch to third position. The rotary magnet therefore 50 will again energize as soon as it falls back and closes its interrupter springs and will step the wipers to the second set of contacts. This buzzer action of the rotary magnet will continue until an idle trunk line 55 is reached and then magnet 18 being no longer held energized will allow the side switch to pass to third position, extending the connection to a selector such as F'. The 60 side switch wiper 25 in passing to third position connects ground through relay 24 to the wiper 23 and thence to the private contact and its multiples of the connected with switch F' to prevent another switch E' 65 from seizing the same.

The subscriber will now again operate his calling device for the second digit 2 and will in this case control the vertical and rotary line relays 26 and 27 of the second selector F'. The line relays of the selector 70 F' were cut off from the line circuit by the movement of the side switch to third position.

The relays 26 and 27 are controlled in the same manner as were the relays of selector 75 E' to first step the wipers vertically by means of the vertical magnet 28, to then operate private magnet 29 to step the side switch to second position, after which the rotary magnet 30 and private magnet 29 80 co-operate to rotate the wipers until an idle trunk line is found, after which the side switch passes to third position to connect ground through back release relay 31 to the private contact of the seized trunk and to 85 cut off the line relays of the switch F' and extend the connection through the line wipers to the line relays 32 and 33 of the seized switch G'. As the switch F' is operated the off normal springs close to light 90 the lamp to indicate to the attendant that the switch is in use.

The next operation of the calling device in response to the third digit 2 causes the operation of the line relays 32 and 33 in 95 the same manner as for preceding switches. Relay 32 operating the vertical magnet 34 to step the wipers to the second level and relay 33 operating the private magnet 35 to step the side switch wipers to second position to start the operation of the rotary magnet 36. This switch G' has one additional side switch wiper 37 which operates to disconnect the vertical magnet in second and third positions to prevent its further 100 operations by the line relays which in this switch remain permanently bridged across the trunk circuit and are not cut off as in the preceding switches. The rotary magnet 36 operates to rotate the wipers to the first idle 110 trunk line after which the private magnet permits the side switch to pass to third position, extending the connection through the line wipers to the connector switch H and connecting ground direct to the private 115 wiper 38 through the side switch wiper 39.

This operation of the calling device for the fourth digit 2 first causes two energizations of the vertical line relay 39 which in turn twice energizes the vertical magnet 41 120 over a circuit from ground through springs 42 and 43, main spring and back contact of private magnet 44, side switch wiper 45 in first position, and through vertical magnet 41 to battery. The following rotary impulse 125 operates relay 40 which closes springs 46 and springs 43 and 47. The closure of springs 46 is without effect at this time but the closure of springs 43 and 47 causes the operation of private magnet 44 to step the 130

side switch wipers to second position. Wiper 45 in second position prepares a circuit for the rotary magnet 48, substituting it for the vertical magnet in the circuit controlled by 5 the vertical line relay 39. The side switch wiper 49 in second position prepares a circuit for the release magnet 50 which will be explained.

Now as the calling device is operated for 10 the last digit "naught," the line relay 39 again operates in response thereto and in this case transmits a corresponding number of impulses through the rotary magnet 48 through springs 42 and 43 to step the wipers 15 onto the set of contacts in the level elected to which the called station B' is connected. After this the rotary line relay 40 will again be operated by the final rotary impulse and will again close springs 46 and springs 43 20 and 47. The private magnet will again energize. In case the called line should be found busy either from calling or being called, then ground will be present on private contact 51 either from the off normal 25 springs of the called subscriber's individual switch C' or from the wipers of some other occupying switch (not shown). In either case, the private wiper 52 being connected with contact 51, then when the relay 40 energizes as pointed out and springs 46 close, 30 a circuit will be completed from ground, contact 51, wiper 52, side switch wiper 49 in second position, springs 46, and through the release magnet 50 to battery. The magnet 35 50 immediately releases all the mechanism of the connector H' and it is restored to its normal position with its off normal springs 53 open and its side switch in first or normal position. The calling subscriber now having completed the calling operations presses 40 the ringing key 12 at the substation. Instead of performing any ringing operation, however, the impulse of ground through the ringing key operates relay 39 which in turn 45 operates the vertical magnet one step and thereby closes the off normal springs 53 to connect the lead from the busy signaling machine 54 to the vertical line conductor. The calling subscriber upon hearing the busy 50 tone will hang up his receiver and release the connection in a manner to be pointed out.

Assuming however, that the called line is idle when connection is made therewith, then no circuit will be closed for the release 55 magnet when relay 40 operates, and the private magnet will permit the side switch wipers to pass to third position. The wiper 45 opens the circuit to the rotary magnet 48 and prepares a circuit in its third position 60 for the ringing relay 54 under control of the vertical line relay. The wiper 49 in third position connects ground direct to the private wiper 52 and thence through the bridge cut off relay 55 of the called line 65 through the off normal springs. Relay 55

energizes to disconnect the vertical and rotary line relays of the called line therefrom to prevent any operation of the switch C' when the called subscriber answers. Other side switch wipers of the switch H' passing 70 to third position extend the connection to the called line through the line wipers and springs of the ringing relay 54. The calling subscriber will now press the ringing key 12 to operate the line relay 39 of the connector which in turn operates the ringing relay 54 to disconnect the called line from the calling line and to connect the ringing generator to the called line to operate the ringer thereof. The called subscriber will 75 remove his receiver and converse with the calling subscriber in response to this signal.

The release of the connection after conversation is accomplished as follows: Should the calling subscriber be the first to 80 restore his receiver, then springs 14, 15 and 16' will be brought into contact to connect ground to both vertical and rotary line conductors simultaneously. This grounding of both line conductors will energize the line 85 relays 32 and 33 of the third selector and the relays 39 and 40 of the connector simultaneously with the results following: Relay 40 will energize the private magnet 44 over a circuit previously traced and relay 39 will 90 therefore complete a circuit from ground through springs 42 and 43, main spring and front contact of the private magnet, and through the release magnet 50 to battery. Magnet 50 returns the switch H' to normal. 95 Relays 32 and 33 in a similar manner close the circuit for the release magnet 56 of the switch G' which releases the switch G' and in turn closes a back release circuit for the preceding selector F' from battery 100 through resistance 57, springs 58, private wiper and contact of switch F', and through the back release relay 31 to ground at the third position of the side switch. Relay 31 closes a circuit for the release magnet 105 59 of switch F' to release said switch and this magnet in turn closes a similar circuit for the back release relay 24 of the individual selector E'. Relay 24 in turn closes the circuit of the release magnet 60 of the 110 switch E' thus restoring the entire connection to normal.

In case the called subscriber is the first to hang up his receiver then the release of the first, second, and third selectors is the 115 same as above described when the calling subscriber hangs up, but the connector is released by the hanging up of the called party as follows: The downward movement of the called subscriber's switch hook 120 closes the release springs 61, 62 and 63 in contact, thereby grounding the called subscriber's line conductors simultaneously to energize the two back release relays 64 and 65 of the switch H'. Relays 64 and 65 con- 125 130

jointly close a circuit for the release magnet 50 of the connector from ground through the three springs controlled thereby and over conductor 63 through the magnet 50 to battery. Magnet 50 releases the connector H' to normal. It will be understood that, should the calling subscriber have desired to release before the call had progressed to the third selector F' then the release 10 would be controlled by the operation of the last switch in the connection, either E' or F' in the same manner as performed by the line relays of the switch G'.

What I claim as my invention is:—

15 1. An automatic telephone system comprising "first selector-switches" which are individual to the subscribers, and which are each provided with normally bridged relays, and also with a bridge cut-off relay 80 for opening the bridge in which the said relays are included when the subscriber to whom the switch is allotted is called.

20 2. An automatic telephone system comprising subscribers' lines, a "first selector switch" for each line, and a suitable number of "connector-switches", together with means for supplying current for the operation of said switches, each "selector-switch" being provided with a pair of relays normally bridged across the subscriber's line to which the switch is allotted, and also with a bridge cut-off relay adapted to destroy the continuity of the bridge in which the relays are included when the subscriber to whom the switch is allotted is called, each bridge cut-off relay having a normally open circuit controlled by one or more of said "connector-switches".

25 3. In an automatic telephone system, the combination of subscriber's lines, a "selector-switch" for each line, each "selector-switch" having an electro-magnetic device normally bridged across the line, and a suitable number of "connector-switches", each "selector-switch" being individual to its allotted subscriber's line, but each "connector-switch" being common to a plurality of subscriber's lines, and each "selector-switch" having a bridge cut-off relay adapted to destroy the continuity of the bridge in which the said electro-magnetic device is included when the subscriber to whom the "selector-switch" is allotted is called, together with means for supplying current, and with which one terminal of each bridge cut-off relay is permanently connected, the other terminal of each bridge cut-off relay being normally connected with one or more of said "connector-switches", substantially as described 55 and for the purpose set forth.

40 4. In an automatic telephone system, the combination of a "selector-switch" provided with a bridge including a switch-operating element, a bridge cut-off relay, a battery, 65 and a normally open circuit including said

bridge cut-off relay and battery, together with a "connector-switch" provided with a plurality of wipers, whereof one is a so-called "private" wiper, the said "private" wiper, when the "connector-switch" is operated, being adapted to close the circuit of the said bridge cut-off relay. 70

5. In an automatic telephone system, the combination of "first selector-switches" which are individual to the different subscribers, and "connector-switches" which are common to the different subscribers, each "selector-switch" being provided with an electro-magnetic device having one terminal normally connected with a switch-contact or contacts of one or more of said "connector-switches", a source of electric current connected with the other terminal thereof, and an operating magnet controlled by said electromagnetic device. 85

6. In a telephone system having a calling subscriber's line, a called subscriber's line, parallel circuit conductors connecting the calling subscriber's line with the called subscriber's line, a condenser in each circuit conductor, and means for setting up and releasing said connection including a battery having one pole grounded, the provision of back bridge relay means bridged between the parallel conducting paths at a point between the condensers and the called line with a connection between the back bridge and the non-grounded pole of said battery, and a called subscriber's bridged relay means together with a bridge-cut-off relay 100 operated by the calling subscriber to open up or cut off the said called subscriber's relay means. 90

7. In a telephone system having calling and called subscriber's lines, with a temporary circuit connection between the two lines including a condenser at each side of the circuit, and having means for setting up and releasing said connection including a pair of relays bridged across the circuit 110 on one side of the condensers, the provision of another pair of relays bridged across the circuit at the other side of said condensers, a battery having one pole grounded and its other pole connected with the middle point 115 of each relay bridge, together with a relay bridge individual to the called subscriber's line and another relay individual to the called subscriber's line and controllable by the calling subscriber for cutting off or 120 opening up the said individual bridge.

8. In a telephone exchange system, the combination of subscribers' telephone lines, a normally closed individual bridge containing electromagnetic devices; normally across each line, an automatic switch controlled by said electromagnetic devices, and an individual relay for each line, said relays adapted to open said bridges when energized and close the same when deenergized, each entire 125 130

bridge being individual to its allotted line, said relays located at the terminals of their lines.

9. In a telephone system, the combination of subscribers' lines, an individual bridge containing electromagnetic devices for each line, an automatic switch controlled by said electromagnetic devices, an individual relay for each line, said relays controlling the 10 continuity of said bridges, each entire bridge being individual to its allotted line, said relays located at the terminals of their lines, and means by which a calling subscriber operates the relay of the called line.

10. In a telephone exchange system, the combination of a telephone line, a bridge across said line, a private normal for said line, a bridge-cut-off-relay for said line, and a circuit for energizing said relay when the 20 line is called, said circuit including said private normal.

11. A telephone system comprising a suitable line, a relay for said line, an electromagnet to be maintained energized when 25 connection is extended to the line and the said relay is not to be used, means for rendering the said relay inoperative when the said magnet is energized, and means for retaining the relay in operative relation to the line when the latter is used for calling in the opposite direction.

12. In a telephone system, a calling subscriber's line, a called subscriber's line, means including automatic switches controlled by direct current for trunking the 35 calling line into connection with the called line, a normally closed bridge across the called line, and means under the control of the calling subscriber for temporarily destroying the continuity of said bridge.

13. In a telephone system having calling and called subscribers' lines, with means for setting up and releasing a connection between said lines including parallel circuit 45 conductors having a condenser in each circuit conductor said means including a bridge of said conductors and means controlled thereby having vertical and rotary motion to find the called line in a selected group, the provision of back bridge relay means bridged between the said parallel conducting paths at a point between the said condensers and the called subscribers' line, a battery having one pole grounded and a connection between 55 the back bridge and the non-grounded pole of said battery together with a called subscriber's bridged relay means and a bridge-cut-off relay operated by the calling subscriber to open up or cut off the bridge of said called subscriber's relay means.

14. In a telephone system having calling and called subscribers' lines, a temporary circuit connection between the two including a condenser at each side of the circuit and means for setting up and releasing said con-

nexion including a pair of relays bridged across the circuit at one side of said condensers, a pair of relays bridged across the circuit at the other side of said condensers, and means controlled by said bridges having 70 vertical and rotary motion to find a called line, the provision of a battery having one pole grounded and its other pole connected to the mid point of each relay bridge, together with a relay bridge individual to the 75 called subscriber's line, and another relay individual to the called subscriber's line and controllable by the calling subscribers for cutting off or opening up said individual relay bridge.

15. In a telephone system, the combination of subscribers' lines, an individual bridge including a switch-operating element; for each line, means having both vertical and rotary motion to seize called 80 lines, one motion to select a group and the other motion to find the called line in the selected group, an individual relay for each line, said relays controlling the continuity of said bridges, and means for energizing 90 the relay of the called line after the completion of both motions.

16. In a telephone exchange system, the combination of a telephone line, a bridge including a switch-operating element across 95 said line, a private normal for said line, a bridge-cut-off relay for said line, a circuit for energizing said relay when the line is called, said circuit including said private normal, and means having vertical and rotary motion to seize said line and close said 100 circuit.

17. A telephone system comprising a called subscriber's telephone line, a relay allotted to said line and controlled by the 105 subscriber thereof, an electromagnet adapted to be energized to place the said relay in inoperative relation to the called line, a circuit for continuously energizing said electromagnet when the line is called, and means 110 having vertical and rotary motion under the control of the calling subscriber for closing said circuit, one motion to select groups and the other motion to find a line in the selected group.

18. A telephone system comprising a subscriber's telephone line, a line relay for said line, a second relay for rendering the line relay inoperative when the line is called, a connector provided with switch wipers and 120 having vertical motion to select groups and rotary motion to connect with the called line in any selected group, a circuit for energizing said second relay by a flow of current through one of said wipers, and means 125 for controlling the operation of the connector to extend connection to said line.

19. In a telephone system, a subscriber's line, a bridge containing a switch-operating element on said line, a relay controlling the 130

continuity of said bridge, means having vertical and rotary motion for seizing said line, one of said motions being necessary for selecting the desired group of lines, and 5 means for energizing said relay when the line is seized.

20. In a telephone system, a line, a bridge containing a switch-operating element normally closed across said line, a bridge-cut-off magnet, a connector provided with line wipers having both vertical and rotary motion to find said line, and a third wiper for closing a circuit through the said magnet when the line is seized.

15 21. In a telephone system, a line, a bridge containing a switch-operating element normally closed across said line, a bridge-cut-off magnet, a connector provided with line wipers having both vertical and rotary motion to find said line, one of said motions being necessary for selecting the desired group of lines, and a local circuit closed through said magnet when the line is seized by the connector.

25 22. In a telephone system having a telephone line and means for signaling on said line, the provision of a bridge across said line at the exchange including a relay, an automatic switch controlled by said relay, 30 and means responsive to the calling party for preventing said relay from responding to the signaling current.

35 23. In a telephone system in which there is a selector and a connector each having vertical and rotary motion and each provided with a bridging relay controlling the vertical and rotary motion thereof, and in which there is means for signaling on the called line after connection has been extended thereto by the selector and connector, 40 the provision of a switch for the called line operative when the said line is used as a calling line, and means for preventing said switch from operating when the called subscriber is signaled.

45 24. In a telephone system having a called line and means for extending a connection to said line and for signaling thereover including an automatic selector switch having vertical and rotary motion and a bridging relay for controlling the vertical and rotary motion thereof, the provision of a trunking switch for the called line operative only when the line is used as a calling line, and 50 means for preventing the said switch from operating when the called subscriber is signaled.

55 25. In a telephone system in which there is a called line, means for extending a connection thereto and for signaling on said called line, comprising an automatic connector switch having vertical and rotary motion, a bridging relay for controlling said vertical and rotary motion, means for

controlling said connector switch in accordance with the last digit of the called number, the provision of an automatic trunking switch for the called line operative only when the line is used as a calling line, and means for preventing the operation of said last switch when the called subscriber is signaled.

65 26. In a telephone system, the combination of first selectors and connectors bridged across the talking circuit; means for controlling said selectors and connectors to extend connection to the called line, and means for automatically rendering the called line inoperative for calling while the connection thereto exists.

70 27. In a telephone system, the combination of a first selector bridged across the talking circuit and having vertical and rotary motion; means for controlling said selector in accordance with the first digit of the called number, said selector provided with a bridging relay controlling the vertical and rotary motion thereof, means for extending a connection to a called line, and means automatically operative to render the called line inoperative for calling while connected with said selector.

75 28. In a telephone system, a first selector bridged across the talking circuit having vertical and rotary motion; means for controlling said selector in accordance with the first digit of the called number, the said selector provided with a bridging relay controlling the vertical and rotary motion thereof, means for extending connection to a 80 called line, a bridge containing a switch-operating element on the called line, and means automatically operative to open said bridge when connection is extended to said line through the medium of said selector.

85 29. In a telephone system in which there is a called line and means for calling and signaling the called subscriber on said line, the provision of a trunking switch individual to said called line having a bridging relay and trunks leading therefrom, said relay being operative only when the line is used as a calling line and means for preventing energizing of said relay when the line is called and the subscriber signaled.

90 30. In a telephone system, a trunk-selecting switch provided with a bridge across the trunk conductors thereof, said bridge including a switch-operating element, means for establishing a talking circuit through 95 said switch, and means for cutting off said bridge during talking.

100 31. In an automatic telephone system, the combination with a metallic telephone line of a selector switch at the central office, a 105 third conductor, a pair of control magnets and a source of current normally connected between the limbs of said line and said third

conductor, and a cut-off relay adapted to maintain a severed connection between said limbs and said third conductor while the line is a called line.

5 32. In an automatic telephone system, a telephone line adapted to be extended in two limbs through the central office, a switch for said line, a pair of electromagnets and a source of current in a by-path from the 10 limbs of said line for controlling said switch, and a cut-off relay adapted to separate said by-path from the external telephone line when said line is a called line.

33. In a telephone system, a line, a bridge

individual to said line and containing switch 15 operating elements normally closed across said line, a bridge cut-off magnet, a connector provided with a pair of talking wipers for finding said line, and a third wiper independent of the talking wipers for closing a 20 circuit through said cut-off magnet when the line is seized as a called line.

Signed by me at Chicago, Cook county, Illinois, this 30th day of November, 1904.

JOHN ERICKSON.

Witnesses:

W. LEE CAMPBELL,
JENNIE NORBY.
